HOERBIGER & CO., OF MAUER, NEAR VIENNA, AUSTRIA

GAS COMPRESSOR

Application filed August 27, 1928, Serial No. 302,324, and in Austria August 27, 1927.

My invention relates to gas compressors of that class in which the air is compressed in a plurality of successive steps that is to say to multi-step gas compressors. 5 My invention consists in that the reservoirs associated to any two successive compression steps are connected by a control element acted upon by the pressures existing in both reservoirs and adapted to maintain a substantially constant ratio between the pressures in both reservoirs.

Heretofore multi-step compressors have been controlled by controlling intake valves of all steps. Now the control of such valves 15 subject to high pressures is very difficult, so that in many cases only the intake valve of the first step was controlled.

But this results in a great reduction of the efficiency and reliability of the compressor, since the reservoir associated to a preceding step is liable to be exhausted while the pressure in the next succeeding reservoir is liable to become excessive. This may happen for instance if a two step compressor is 20 used for a locomotive operated by a Diesel motor and the reservoir associated to the first step has to supply air under pressure for operating the brakes while the reservoir associated to the second or high pressure step has 25 to supply the air under pressure for starting. The frequent supply of air under pressure for operating the brakes may then result in an exhaustion of the corresponding reservoir.

30 The drawing shows diagrammatically, a vertical section view through a constructional form of a two stage compressor constructed in accordance with the present invention.

Referring to the drawing it will be noted 40 that the compressor has a differential piston comprising a lower piston 1 and an upper piston 6 concentrically mounted with and upon the lower piston and of less diameter than it. The lower piston operates in a cylinder 1^a and serves to compress atmospheric air delivered to that cylinder through an intake valve 2. The compressed air is discharged through a delivery valve 3 and pipe line 3^a, to a reservoir 4, from which the compressed air may be withdrawn through exit 5

therein for use in consumption devices, not shown.

The upper high pressure piston 6, operates in a cylinder 6^a. This cylinder 6^a has air under pressure supplied to it from reservoir 4 through a pipe line 7 connecting the reservoir and cylinder. A high pressure intake valve 7^a is located in intake pipe 7 and a high pressure delivery valve 8^a is located in a delivery pipe 8. This delivery pipe connects the high pressure cylinder 6^a and a high pressure reservoir comprising two interconnected chambers 10, 11 communicating with each other through an automatic valve 9.

If the pressure in the chamber 11, communicating with a consumption device not shown through a pipe 12, is reduced, air under pressure flows from the chamber 10 into the chamber 11 through the automatic valve 9. Therefore the pressures existing in the chamber 10 and the chamber 11 are always substantially the same.

Final delivery of high pressure air may take place through exit 12 of the reservoir 11. It should be noted that the intermediate chamber 10 may act as a cooling chamber.

In order that the ratio of the pressures in the high and low pressure tanks may be maintained at a fixed and predetermined value the chamber 10 and reservoir 4 are connected 80 by a duct containing valve 13 having a differential piston geometrically similar to the pump piston hereinbefore described. This valve piston operates in a cylinder 14^a and comprises a lower reduced stem 14^c and an upper enlarged head 14^b in communication with the reservoir 4 through pipe 5^a. The stem 14^c seats upon port 13^a in the communicating duct between reservoirs 10 and 4 to prevent passage of high pressure air from reservoir 10 to reservoir 4 except when the pressure in the reservoir 10 is so much greater than the pressure in reservoir 4 that port 13^a will be opened by the excess pressure on the stem 14^c, thus allowing high pressure air to 85 enter reservoir 4.

To assist the valve in maintaining the port 13^a closed, a coil spring 15 is located within the cylinder 14^a and presses on the head 14^b. So long as the proper ratio of pressures exists 90

the valve 13 will be in equilibrium, but when the pressure in the reservoir 4 drops the valve 13 will open admitting air from chamber 10.

Each stroke of the piston 6 takes air from reservoir 4 and tends to increase the pressure in chamber 10 by a certain amount, and if the pressure at which the air is delivered to piston 6 is high then the pressure at which the air is delivered to the chamber 10 will be that high plus the amount of compression it has been subjected to under piston 6. Thus on account of the fact that the air in chambers 10 and 12 comes from reservoir 4 the ratio of pressures between reservoirs 10 and 4 can not decrease by the building up of a high pressure in reservoir 4.

The low pressure intake valve 2 is provided with a stopping device 16 connected with the control valve 17 communicating with the high pressure chamber 10.

What I claim is:

1. In a multistage gas compressor, the combination of at least two compressing cylinders and pistons working therein, a reservoir for each of said cylinders communicating with the delivery sides of said cylinders, a duct connecting the reservoirs of two successive compressor stages, and means adapted to maintain a substantially constant ratio between the pressures in the said reservoirs, said means being included in said duct and being responsive to the pressures in the two reservoirs which it connects.

2. In a multistage gas compressor, the combination of at least two compressing cylinders and pistons working therein, a reservoir for each of said cylinders communicating with the delivery sides of said cylinders, a duct connecting the reservoirs of two successive compressor stages, and means adapted to maintain a substantially constant ratio between the pressures in the said reservoirs, said means being included in said duct and being responsive to the pressures in the two reservoirs which it connects, and a delivery chamber communicating with one of said reservoirs.

3. In a multistage gas compressor, the combination of at least two compressing cylinders and pistons working therein, a reservoir for each of said cylinders and communicating with the delivery sides of said cylinders, a duct connecting the reservoirs of two successive compressor stages, and means adapted to maintain a substantially constant ratio between the pressures in the said reservoirs said means being included in said duct and being responsive to the pressures in the two reservoirs which it connects, and a delivery chamber communicating with one of said reservoirs by a passage having an automatic valve therein.

4. In a multistage gas compressor, the combination of at least two compressing cylinders and pistons working therein, a reser-

voir for each of said cylinders communicating with the delivery sides of said cylinders, a duct connecting the reservoirs of two successive compressor stages, and means adapted to maintain a substantially constant ratio between the pressures in the said reservoirs, said means including a piston having opposite faces differing in area and acted upon by the pressures in said reservoirs.

5. In a multistage gas compressor, the combination of at least two compressing cylinders and pistons working therein, a reservoir for each of said cylinders communicating with the delivery sides of said cylinders, a duct connecting the reservoirs of two successive compressor stages, and means adapted to maintain a substantially constant ratio between the pressures in the said reservoirs, said means comprising a piston having opposite faces differing in area and acted upon by the pressures in said reservoirs, the smaller face controlling the duct between said reservoirs.

6. In a gas compressor having a plurality of reservoirs successively connected, each having a different pressure, means to maintain a predetermined ratio of pressures between said reservoirs said means comprising a duct connecting successive reservoirs and having a one way valve therein, said valve being adapted to open when said ratio increases due to an increase in pressure in the high pressure reservoir or a decrease in pressure in the low pressure reservoir.

In testimony whereof I have affixed my signature.

ALFRED HOERBIGER.
